UNITED STATES PATENT OFFICE.

SWINFEN BRAMLEY-MOORE, OF WHITE PLAINS, NEW YORK, ASSIGNOR OF ONE-HALF
TO JOHN MCINTYRE, OF PORTOBELLO, MIDLOTHIAN, SCOTLAND.

GRINDING, REFINING, AND MIXING MACHINE.

Application filed October 7, 1927. Serial No. 224,683.

The present invention relates to grinding, refining and mixing machines for grinding, refining and mixing cocoa beans, chocolate, chemicals and other similar substances, and 5 aims to provide a novel assembly of a resilient grinding element and pressure member with which said element moves, this invention being an improvement over the device disclosed in application Serial No. 153,011, 10 filed December 6, 1926, by John McIntyre.

With the foregoing and other objects in view, which will be apparent as the description proceeds, the invention resides in the construction and arrangement of parts, as 15 hereinafter described and claimed, it being understood that changes can be made within the scope of what is claimed, without departing from the spirit of the invention.

The invention is illustrated in the accompanying drawing, wherein—

Figure 1 is a rear edge view of the improved device.

Fig. 2 is an end view thereof.

The grinding element comprises a plate 25 or blade 7 composed of suitable resilient sheet metal, which is elongated transversely of the line of movement thereof or parallel to the axis around which the grinding element moves. The blade 7 is carried by one 30 or more blades or plates 8, also of resilient sheet metal, with joint means 9 between the blade 7 and plates 8. Rods 10 are disposed on the face of the blade 7 and are spaced apart on the opposite sides of the longitudinal line of the joint 9, said rods being attached to the blade 7 in the manner disclosed in the aforesaid application.

The joint 9 is a hinge joint to permit of 40 flexing action between the blade 7 and plate 8, and to distribute the pressure from the plates 8 equally to the rods 10 in front and in rear of the hinge joint. The hinge joint includes lugs 11 riveted or otherwise secured to the blade 7 and plates 8 and one or more hinge rods 12 extending through said lugs. Lugs or blocks 13 are also riveted or otherwise secured to the blade 7 and plates 8 and complement the lugs 11, said lugs 11 having rounded portions seating in rounded notches 45 with which the lugs 13 are provided, in order that the pressure of the plates 8 is transmitted to the blade 7.

The plates 8 are secured in any suitable manner to a rocker 14 carried by a rotor 15, and an annular set of grinding elements is 55 employed within a cylinder 16 with the rods 10 contacting with the inner surface of the cylinder to crush, grind, refine or mix the material between said rods and cylinder.

The rocker 14 is adjusted to move the 60 plates 8 toward the cylinder 16, thereby bending or springing the plates 8 and applying spring pressure to the blade 7 and rods 10. The hinge joint 9 permits of relative swinging motion between the blade 65 7 and plates 8 in order that the blade 7 may adjust itself to the surface of the cylinder 16, and the front and rear rods 10 will also receive equal pressure so as to equalize wear thereon, whereas the rods in the construction 70 disclosed in the aforesaid application will wear unevenly as well as receiving varying pressures. The blade 7 is also sprung under the pressure of the plates 8 which is transmitted through the hinge joint 9. With the 75 use of the hinge joint 9 the grinding element is self-adjusting and the load or pressure is distributed uniformly between the front and rear rods 10, which has been found to decrease the power required as well as to even- 80 ly distribute the wear and increase the life of the grinding element.

Having thus described the invention, what is claimed as new is:—

1. A device of the character described 85 comprising a resilient blade having front and rear grinding portions, and pressure applying means hingedly connected to said blade at a point to apply pressure between said front and rear grinding portions. 90

2. A device of the character described comprising a resilient blade having front and rear grinding portions, pressure applying means including a resilient plate, and a hinge joint connecting said blade and plate. 95

3. A device of the character described comprising a resilient blade having front and rear grinding portions, pressure applying means including a resilient plate, and a hinge joint connecting said blade and plate 100 and arranged to transmit the pressure from said plate to the blade at a point between said front and rear grinding portions.

4. A device of the character described

comprising a resilient blade having front and rear grinding portions, pressure applying means including a resilient plate, hinge lugs secured to said plate, a hinge rod ¹⁰
5 tending through said lugs to hingedly connect the blade and plate, and lugs complementing the hinge lugs and secured to said blade and plate, the first-named lugs having

rounded portions and the second-named lugs having rounded notches in which said rounded portions are seated to transmit the pressure from said plate to said blade.

In testimony whereof I hereunto affix my signature.

SWINFEN BRAMLEY-MOORE.
